METAL FORM CLAMPING DEVICE

William Allen Jennings, Des Moines, Iowa, assignor to Economy Forms Corporation, Des Moines, Iowa, a corporation of Iowa

Application July 27, 1936, Serial No. 92,754

1 Claim. (Cl. 25—131)

In the art of sheet metal forms for concrete structures it is customary to provide sheet metal forms in relatively small sections with flanges extended outwardly from the edges thereof, and to provide holes in said flanges through which bolts or other clamping devices may be extended to rigidly hold the forms together.

My object is to provide means of simple, durable and inexpensive construction by which said mould forms may be readily, quickly and easily clamped together with sufficient firmness to withstand the shocks and jars to which such structures are subjected in use, and particularly when the cement between the forms is tamped or agitated, and which clamping devices may be readily, quickly and easily detached when the forms are being removed from a finished concrete structure.

Referring to the accompanying drawing, Figure 1 shows a perspective view of my improved clamping device.

Figure 2 shows a side elevation of one of my improved clamping devices applied to the flanges of a metal form and illustrated in clamped position. The dotted line shows the position of the

Figure 3 shows a transverse sectional view through portions of two abutting metal forms and their flanges, and through my improved clamping device applied thereto, illustrating a form of the invention in which the clamping device is frictionally held in position by bending the adjacent portions of the flanges of the metal form.

Figure 4 shows a similar view illustrating a modification in which the jaws of the clamping device are retained in position by springing into openings in the flanges of the forms.

Figure 5 is a similar view illustrating another modification in which the clamping device is held in position on the flanges by bending the flange laterally to one side and employing the resiliency of the flange to hold the clamp in place.

Figure 6 shows a similar view of another modification in which the clamping device is held in place by a projection on the resilient jaw of the clamping device being sprung into position below the looped portion of the flange of the mould form.

Figure 7 shows a similar view of another modification in which both jaws of the clamping device are resilient, and in this view they are shown spread apart by the thickness of the overlapped portions of the flange; and

Figure 8 shows a view of the same form of the invention with the resilient jaws sprung to posi-

tion engaging the lower edges of the overlapped portions of the flange of the metal forms.

Referring to the accompanying drawing, the clamping device, as clearly shown in Figure 1, comprises a body portion 10, with a handle portion 11 at one end and an extension 12 at the other end, to which extension there is fixed a pin 13. Between the handle portion 11 and the extension 12 there are two jaws 14 and 15. In this figure the two jaws are provided with extensions 16 and 17 at their ends furthest from the body, the extensions projecting toward each other.

This entire clamping device is preferably formed of a single piece of resilient metal and is preferably cast complete in one piece so that it is cheap to manufacture and does not need any machine.

The metal forms which I employ in connection with my invention are composed of relatively flat body portions 18 made of resilient sheet metal and provided with flanges 19 which extend from the edges of the body substantially at right angles, and their outer ends are folded back upon the flanges at 20, the edges of the members 20 being spaced apart from the body 18. These flanges are provided with a series of openings 21 preferably equally spaced apart throughout their entire lengths, so that the clamping device may be placed on any part of the flange.

In the form of the invention illustrated in Figures 1, 7 and 8, I apply the clamping device as follows: I first insert the pin 13 through the aligned openings 21 in two of the flanges of the metal form. I then grasp the handle portion and turn it pivotally centered upon the pin 13 until the jaws 14 and 15 engage opposite sides of the two flanges, as shown in Figure 7 where they are seen to be slightly sprung apart. I then, preferably with a hammer, strike the handle and drive the jaws toward the bodies of the forms until the projections 16 and 17 have passed below the lower edges of the flanges 20, whereupon the jaws spring toward each other and thereby yieldingly hold the clamping device in position and to clamp the two adjacent mould forms firmly together.

In practice I have found that with my improvement the forms are held together with sufficient rigidity to withstand the tamping or agitation to which the concrete in the mould forms is ordinarily subjected.

When it is desired to dismantle the mould form the operator may, by grasping the handle 11 or by using a lever to pry them outwardly, quickly and easily swing them to position with the jaws

beyond the ends of the overlapped flanges, and then the handle may be moved laterally, either by hand or with the use of a hammer, to withdraw the pin. Obviously, these operations of applying 5 the clamping device, or removing it, can be accomplished very quickly and easily by unskilled labor.

In the modified form illustrated in Figure 6 I have shown a projection 22 on one of the jaws 10 only, the other one being left smooth and straight and parallel with the adjacent portion of the flange of the form. With this construction the operation of applying or removing the clamping device is the same as that hereinbefore described, except that only one projection 22 is employed to hook under the adjacent edge of the overlapped portion of the flange.

In Figure 4 I have shown another modification 20 in which the clamping jaws are somewhat shorter in length than that shown in Figure 7, and otherwise the same only the projections 23 and 24 thereon are so positioned as to enter the adjacent openings 21 in the flanges of the mould forms.

In the modification shown in Figure 5 I have 25 shown one of the jaws 25 to be of the same length as the adjacent overlapped portion 20 of the flange 19, and the other jaw is provided with an extension 26 at its lower end to pass under the lower edge of the adjacent overlapping portion 20 of the flange of the mould form. In this modification the clamp is held in position both by the resiliency of the flanges 19 which are bent laterally when this modified form of the device is applied, and by the extension 26 being moved to 30 position under the shoulder formed by the adjacent overlapping member of the flange.

In the modified form illustrated in Figure 3 I have shown the inner adjacent surfaces of both 35 jaws, and slightly curved, and one jaw 27 terminates at about the lower end of the overlapping portion of the flange, while the other jaw is longer and has a projection 28 that ex-

tends toward the adjacent flange below the overlapping portion. In this form of the invention the resiliency of the flanges themselves aid in holding the clamping device in position, and in this form of the invention the part indicated 5 as 28 constitutes an inwardly extended projection which functions somewhat similar to the projections 16 and 17 of the form of the invention illustrated in Figure 1.

In practical operation with any of the forms 10 of my invention herein described I can easily, readily and quickly insert the pin 13, drive the handle toward the flanges, turn the handle in the direction toward the flanges of the metal forms and then drive the body 10 with a hammer, 15 or otherwise, to position for causing one of the projections on the inner face of the jaws to position below the overlapping edge of the flange or into the pin openings 21, and when this has been done the resiliency either of the jaws themselves 20 or of the flanges securely holds the clamps in position and the metal forms rigidly in engagement with each other.

I claim as my invention:

A clamping device comprising a lever, a fulcrum pin extended laterally from one end portion of the lever, and a pair of jaws formed integral with the lever and of resilient material, the space between the ends of the jaws furthest from the lever being less than the space between the remainder of the jaws and whereby when the jaws are forced upon two articles to be clamped together and which are relatively thick at their outer edges and of less thickness at a point spaced from said outer edges, the jaws will be forced 25 apart during the time when the jaws are moving over said relatively thick portions and then spring toward each other and form a frictional locking engagement with said articles when the end portions of the jaws reach said less thick portions of 30 35 the articles.

WILLIAM ALLEN JENNINGS.
